United States Patent Office

Des. 225,969
Patented Jan. 16, 1973

225,969

HAMPER

Marvin D. Rosenberg, Glencoe, Ill., assignor to Convenience Locker Corp., Chicago, Ill.

Filed Nov. 6, 1970, Ser. No. 25,858

Term of patent 14 years

Int. Cl. D7—06

U.S. Cl. D49—8.2

FIG. 1 is a front perspective view showing my new design for a hamper, the unseen right side of the hamper being substantially identical to the shown left side and the unshown rear side and bottom forming no part of my design; and

FIG. 2 is a front perspective view of a modified form of my design.

I claim:

The ornamental design for a hamper, substantially as shown and described.
